Primary Examiner — Cynthia Ramirez(74) *Attorney, Agent, or Firm* — Patterson Thuente Pedersen, P.A.(57) **CLAIM**

We claim the ornamental design for a log cart, as shown and described.

DESCRIPTION

FIG. 1 is a perspective view of a log cart showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines in the figures are included for the purpose of illustrating portions of the log cart and forms no part of the claimed design.
